UNITED STATES PATENT OFFICE.

NESTOR JIMÉNEZ PILLOT, OF SANTIAGO, CUBA.

AUTOMATIC NEEDLE-DISPENSING DEVICE.

Application filed August 10, 1926. Serial No. 128,469.

This invention relates to a device, in the form of an attachment for a sound box of a sound reproducing machine, the purpose of which is to readily supply needles to replace the worn needle in an improved needle holding device.

Briefly, the invention has reference to an improved needle holding device which is associated with the customary stylus bar which 10 is in turn connected with the diaphragm on the sound box. This holder is constructed to permit the worn needle to be readily displaced and a new needle to be inserted and disposed in place for operation in rapid succession.

The invention also has reference to an improved container for the needle to accommodate a multiplicity of the same, together with a spring pressed plunger for ejecting 20 the needles one at a time.

The objects and advantages of the invention will become apparent from the following description and drawings.

In the accompanying drawings forming 25 a part of this application and in which like numerals are employed to designate like parts throughout the same:

Figure 1 is an elevational view of a device constructed in accordance with this invention, showing the same associated with 30 a conventional form of sound box, the needle feeding device being disposed in one position.

Figure 2 is a similar view showing the device in a position for discharging one of the 35 needles and placing another needle in place.

Figure 3 is an enlarged sectional detail view of the needle holding device at the bottom of the sound box.

40 Figure 4 is a cross section taken approximately upon the plane of the line 4—4 of Figure 3.

Figure 5 is a horizontal section taken on the line 5—5 of Figure 2 looking downwardly.

Figure 6 is a similar view to Fig. 5 showing the parts in a different position.

Fig. 7 is a sectional view taken on the line 7—7 of Fig. 1.

50 Figure 8 is also a similar view, the same being taken on the line 8—8 of Figure 2, and

55 Figure 9 is an enlarged side elevational view observing the structure shown on the opposite sides of the device to that represented in Figures 1 and 2.

Referring to the drawings in detail, the reference character 1 designates generally the sound box including the attaching neck 2 and diaphragm stylus bar 3. In accordance with the present invention a novel needle holding device 4 is connected with the stylus bar, and spaced supporting ears 5 are connected with the sound box 1. The needle feeding device, which is mounted on 60 these ears 5 is represented by the reference character 6.

The needle holding device comprises an enlarged channel shaped receiver 7 which is open at its bottom to permit the needle to 65 be ejected as represented in dotted lines in Figure 2. Extending outwardly from one side wall of the channel are arms 8 cooperable with resilient arms 9 between which the needle 10 is held while the machine is in 70 operation. These arms are so constructed as to firmly hold the needle in a vertical operating position. Moreover, the needle holding device is connected with the stylus bar 3 in a manner to impart vibrations thereto for 75 transmission to the diaphragm, in the usual way.

The dispensing device 6 comprises a box 11 provided with spaced lugs 12 pivotally connected at 13 to the aforesaid ears 5, thus 80 permitting the box to be swung toward and from the sound box. This connection between the box and the ears of the U-shaped member carried by the sound box is represented plainly in Figure 8. The box is open 85 on one side and is of hollow formation to provide a receptacle for the needles 14 to be used.

On the interior of the box is an arcuate partition 15 dividing the box into a receiving chamber or hopper 16. A guide 90 bracket 17 is also found in this hopper to guide the needles into the restricted passage shown. The open side of the box is closed by a spring actuated cover 18 having an operating flange 19. The box is formed with a discharge opening from which a keeper finger 20 of curved formation extends. Operable with this finger is a plunger 21 for 95 ejecting the needles one at a time. This plunger is provided with a slot cooperable with a guide 22 and it is also provided at its outer end with the finger piece 23 and between this finger piece and the box is a coil spring 24 for moving the plunger in a direction from right to left in Figures 5, 6, 100 110 and 7.

It will be noticed from Figure 5 and also

Figure 9 that a flat spring 25 is employed to bear against one side of the plunger to hold it in frictional engagement with the finger 20. In addition, the plunger terminates in an extension 26 forming a pocket for aiding in the ejection of the needle. At this time, attention is directed to Figure 9 wherein the discharge slot 27 is shown plainly, together with the plunger holding spring 25, the guide finger 20, and a similar guiding member 28, the shape of this guide member being shown better in Figure 7.

In practice, a plurality of the needles are placed in the hopper 16 of the box and are guided into the passage formed between the partition wall 15, the adjacent wall of the box and the bracket 17. Here, they are permitted to enter the discharge slot 27 one at a time by first entering the pocket formed between the end of the plunger 21 and its extension 26. Obviously then by pushing the plunger in a direction against the action of the spring, the needle shown in Figure 6 will be forced against the finger 20 as shown in Figure 5 and between the retaining arms 8 and 9 of the needle holding device 4. Before the new needle, thus ejected, is inserted between these arms and clamped in place, the old needle is pushed out of the arm and into the channel 7 and allowed to drop by gravity through the open bottom of the channel onto the record, or record table, from where it is removed. A spring is employed to maintain the dispensing device in an out of the way position as shown in Figure 1, but it may be readily moved down-

wardly to needle ejecting and inserting position as shown in Figure 2.

From the foregoing description and drawing it is obvious that I have produced a novel device for dispensing needles one at a time and for simultaneously discharging an old needle and putting a new needle in its place, the compactness and convenience of such a device being evident, as are details and relative arrangement. Moreover, the operation is clear together with the various features and advantages accompanying the same. Consequently, a more lengthy description is thought unnecessary.

While the preferred embodiment of the invention has been shown and described, it is to be understood that minor changes coming within the field of invention claimed may be resorted to if desired.

Having thus described the invention, what I claim as new is:

In a structure of the class described, in combination, a sound box including a diaphragm, a stylus bar connected with said diaphragm, a needle holding device connected with said stylus bar, said device embodying a channel and outstanding needle gripping and retaining arms, a needle dispensing device pivotally mounted on the sound box and adapted to force one needle from between said arms into said channel, and to subsequently put a new needle in place between the arms.

In testimony whereof I affix my signature.

NESTOR JIMÉNEZ PILLOT.
